The ornamental design for a decorative medallion for trading cards as shown and described.

DESCRIPTION

FIG. 1 is a top front perspective view of a decorative medallion for trading cards, showing my new design;

FIG. 2 is a top rear perspective view thereof, the rear elevation view being a mirror image thereof;

FIG. 3 is a front elevation view thereof;

FIG. 4 is a rear elevation view thereof;

FIG. 5 is a left-side elevation view thereof, the right-side elevation being a mirror image thereof;

FIG. 6 is a top plan view thereof, the bottom plan view being a mirror image thereof; and,

FIG. 7 is a reduced front elevation view of the decorative medallion for trading cards, shown in a used condition.

The broken lines showing a trading card in FIG. 7 depict environmental subject matter that forms no part of the claimed design.

The use of stippling indicates a contrasting appearance with the adjacent line-shaded portions of the decorative medallion for trading cards.
